UNITED STATES PATENT OFFICE

GEORGE H. BARBER, OF NEW ROCHELLE, NEW YORK, ASSIGNOR TO BOND ELECTRIC CORPORATION, OF JERSEY CITY, NEW JERSEY, A CORPORATION OF DELAWARE

DESIGN FOR A COMBINED FLASH-LIGHT CAP AND HANGER RING

Application filed June 29, 1932. Serial No. 44,220. Term of patent 14 years.

To all whom it may concern:

Be it known that I, GEORGE H. BARBER, a citizen of the United States, and residing in the city of New Rochelle, county of Westchester, and State of New York, have invented a new, original, and ornamental Design for a Combined Flashlight Cap and Hanger Ring, of which the following is a specification, reference being had to the accompanying drawing, forming a part thereof.

Figure 1 is an elevational view of the cap with its hanger open or extended.

Figure 2 is a plan view looking from above

in Figure 1, with the hanger secured in position in the groove which extends inwardly from one end of the bottom cap and the walls of which converge.

Figure 3 is an end view of the cap looking at the end of the groove.

I claim:

The ornamental design for a combined flashlight cap and hanger ring, as shown and described.

This specification signed this 31st day of May, 1932.

GEORGE H. BARBER.
